WINDOW STRUCTURE HAVING A COMBINED LIFT AND LATCH DEVICE

Henry J. Bianco, Baltimore, Md., assignor to The Burch Company, Baltimore, Md., a corporation of Maryland

Application June 30, 1953, Serial No. 364,986

10 Claims. (Cl. 189—72)

The present invention relates to a metal window construction and, more particularly, to such a construction for a sliding metal window sash or screen having a combined latch and lift device associated therewith.

It is an object of the present invention to provide a combined latch and lift whereby a window sash or screen can be raised and latched in any desired position and/or lowered without shifting of the operator's hands from a pair of grip members attached to the sash or screen.

Another object of the invention is to provide a sliding window sash or screen having a pair of combined latch and lift devices associated therewith so that the window sash or screen may be raised or lowered, smoothly and evenly, to or from an adjusted position or maintained in an elevated latched position without cocking.

Still another object of the invention is to provide a construction whereby a metal window or screen can be raised to a selected position by exerting only an upward force but in which a latch bolt must be manually retracted by exerting a laterally applied force before the window can be lowered.

Yet another object of the invention is to provide a frame and track arrangement to provide for the reception of a latch carried by a vertically sliding window or screen.

Another object of the invention is to provide a process whereby a grip member for the present combined latch and lift device may be readily and economically manufactured of sheet metal.

Other and further objects of the invention will be apparent from the following detailed description taken in conjunction with the drawings in which:

Fig. 1 is a fragmentary elevational view of a window sash in lowered position and equipped with a pair of the latch and lift devices of the present invention;

Fig. 2 is an enlarged fragmentary view partly in elevation and partly in section showing a corner of the window sash illustrated in Fig. 1 in full lines in its lowered position, and showing the sash in a raised or elevated position in dot-and-dash lines;

Fig. 3 is a vertical sectional view taken on the line 3—3 of Fig. 2 looking in the direction of the arrows;

Fig. 4 is a horizontal sectional view taken on the line 4—4 of Fig. 2, looking in the direction of the arrows;

Fig. 5 is a top plan view showing the blank from which the grip portion of the instant latch actuator and grip or lift is manufactured; and

Fig. 6 is a perspective view showing the grip portion in final form.

In the drawings, the numeral 1 generally designates a metal frame adapted to be mounted in a wall opening. The window frame 1 includes a horizontal sill member 2 and horizontal top member (not shown), the ends of which are interconnected by a pair of vertical side members 3 of similar construction. The side members 3 include a web portion 4 having a depressed longitudinally extending channel 6 formed therein as shown in Fig. 4.

Each of the side frames 3 has associated therewith a sash guide track 7, which includes a U-shaped portion 8

2

comprising a pair of leg portions 9 joined by a base portion 11. The tracks 7 are more completely disclosed in my application Serial No. 365,056, filed June 30, 1953, which issued into a patent bearing No. 2,775,003.

5 The base portion 11 immediately overlies channel 6 and is provided with a series of spaced apertures 12 for a purpose which will be brought out fully hereinafter. The apertures 12 may conveniently be formed by striking out tabs 13 from the base portion 11 in an inward direction into the channel 6, with the tabs joined to the base portion 11 at their upper end to form an inclined cam surface in conjunction with each of the apertures 12.

10 The guide tracks 7 receive a window sash, generally designated by the numeral 14, for vertical sliding movement in the U-shaped portion 8. Ordinarily, weather stripping (not shown) will be employed to seal the space between the window and the leg portions 9 of the U-shaped portion 8.

15 While a window 14 has been shown for the purpose of illustrating the present invention, it is to be understood that the invention is equally applicable to a vertically reciprocating window screen (not shown).

20 The window 14 includes a horizontal top rail 16 and a horizontal bottom rail 17 joined by vertical side rails 25 18, all of the rails being formed preferably of extruded aluminum alloy shapes. The top and bottom rails may be secured to the side rails by means of a screw 19 threaded into a metal block 21 secured by a rivet 21a to the side rails 18 at each end. For a more detailed description of the block 21 and the sash assembly, reference is made to my copending application Serial No. 365,055, filed June 30, 1953, which issued into a patent bearing No. 2,782,885.

25 The latch and lift device of the present invention is 30 associated with the bottom rail 17, which as shown particularly in Fig. 3, includes a pair of vertical side walls 22, joined by a pair of spaced horizontal web members 23, so as to provide the bottom rail 17 with a hollow interior portion 24 and an exterior portion presenting a 35 flat vertical surface 26. Side walls 22 extend beyond the web members 23 in both directions to form an upper glazing groove 27 and a lower groove 28, which may contain weather stripping 29 to seal against the sill 2 of window frame 1.

40 The combined latch and lift device comprises a latch bolt 30 guided for horizontal sliding movement in the lower half of the hollow interior portion 24 of bottom rail 17 by means of a pair of opposed guide ribs 31. A coil spring 32, bearing at one end against the flat inner 45 end 33 of latch bolt 30 and at the other end against a tongue 34 struck downwardly from the upper web member 23, normally urges the latch bolt 30 outwardly. The latch bolt 30 is bevelled at its outer end as at 20 to provide a cam surface lying in the same general vertical 50 plane as that formed by the tabs 13.

55 To effect movement of latch bolt 30 and raise or lower the window, there is provided exteriorly of the bottom rail 17 a grip member generally designated by the numeral 35, which comprises a flat base portion 36, adapted to slide over the flat vertical surface 26 of bottom rail 17, and a finger gripping flange 37 extending longitudinally from the upper edge of the flat base portion 36.

60 The grip member 35 may conveniently be manufactured from a stamped blank B of sheet metal such as aluminum of the configuration shown in Fig. 5 of the drawings.

65 The blank B includes an elongated narrow portion 38, which forms the finger gripping flange 37 and an adjoining relatively short and wide portion 39 which forms the flat base portion 36. The two portions are joined only along a medial zone M thereof and the relatively short and wide portion 39 has rounded corners 39' extending

from the sides thereof and terminating at the juncture of the two portions. To present a pleasing appearance and to avoid sharp corners in the finished grip the elongated narrow portion 38 may have its outermost corners rounded as at 38'.

The grip member 35 is formed by bending the blank along the medial zone M, at which the portions 38 and 39 are joined, until they lie in planes at right angles to each other. The ends of the elongated narrow portion 38 are generally tab-like and may then be bent to conform with the arcuate boundaries of the corners 39' as shown in Fig. 6. It has been found that if fairly heavy gauge material is employed, it is unnecessary to secure the tab ends of the flange 37 to the rounded corners 39'. A pair of holes 40 is preferably punched in the portion 39 before the blank B is bent along the region M.

Latch bolt 30 and grip member 35 are rigidly interconnected by means of a pair of spaced screws 41 having threaded portions 43 received in a pair of correspondingly spaced threaded openings 42 in the latch bolt. Above the threaded portion 43 of screws 41 is an enlarged portion 44 forming an abrupt shoulder 46. The enlarged portion 44 terminates in a still further enlarged head 47 provided with a flat under portion 48.

The screws 41 pass through the pair of spaced apertures 40 in base portion 36 of the grip member 35, the apertures 40 conforming closely to the dimensions of the enlarged portions 46, and through a pair of underlying spaced slots 51 in the inner of the side walls 22 of bottom wall rail 17. The distance between shoulder 46 and the under surface 48 of head 47 is made such that when the screws 41 are screwed home, there will be just sufficient clearance between the vertical surface portion 26 of rail 17 and the adjoining surface of the base portion 36 or grip member 35 that easy horizontal sliding motion is possible.

The width of slots 51 may conform closely to the diameter of the enlarged portion 44 of screws 41 but their length is such that they limit, in one direction, the outward movement of latch bolt 30 under the urging of coil spring 32 and, in the other direction, the retraction of the latch bolt 30 to a position wholly within the hollow interior portion of rail 17 by manual effort against the force of the spring 32.

It is preferable to install one of the latch lift devices at each side of the window sash 14, so that the window will be held at a selected elevated position, with no tendency for the window to cock. It is to be understood, however, that in the interest of economy the combined latch and lift device could be installed in only one lower corner of the window and a lift member only rigidly secured at the other corner.

From the above description, the operation of the combined latch operator and lift device will be readily apparent. If the window or screen is in lowered position, it is only necessary to insert the fingers under the flange portion 37 of grip 35 and exert an inward lateral force to retract the latch bolts 30. The window or screen may then be raised to approximately the height desired and the inward lateral force relaxed to permit the coil springs 32 to urge latch bolts 30 toward their extended position. By then lowering the window the latch bolts 30 will project into the nearest of the aligned apertures 12 and maintain the window at the desired elevation in a positive manner.

To lower the window it is only necessary to again exert a manual inwardly directed lateral force to retract the latch bolts 30 and force the window downwardly into any selected lowered position.

It is to be noted, that, if desired, the window can be raised without retracting latch bolt 30. The tip of the latch bolt 30 will readily slide along web portion 11 and even though the latch bolt will be projected into each successive aperture 12, it will be readily cammed therefrom by the complementary cam surfaces formed by the

bevelled end 20 of latch bolt 30 and the tab 13 struck from the base portion 11 to form the aperture 12.

It will be understood that various changes may be made in the details of construction of the combined operator 5 latch and lift device described herein without departing from the principles of the invention and the scope of the annexed claims.

I claim:

1. A combined latch operator and lift device for a vertically sliding closure member having a bottom rail of extruded aluminum including a hollow interior portion and an exterior portion presenting a flat vertical surface, comprising: a latch bolt guided for longitudinal sliding movement within said hollow interior portion; a hand grip member for raising and lowering said closure member having a finger engaging portion and a flat base portion, said hand grip member being positioned outside of said bottom rail and being arranged for sliding movement laterally of said closure member over said flat vertical surface of said bottom rail, said finger engaging portion being an integral flange extending along the upper edge of said flat base portion and disposed perpendicular to said flat base portion; means extending from said flat base portion and through elongated slots in said bottom rail 15 and connecting said hand grip member to said latch; spring means normally urging said latch bolt to extended position; and means rigidly interconnecting said latch bolt and said grip member whereby lateral movement of said grip member will cause a corresponding longitudinal movement of said latch bolt.

2. A combined latch operator and lift device for a vertically sliding closure member having a bottom rail of extruded aluminum including a hollow interior portion and an exterior portion presenting a flat vertical surface, comprising: a latch bolt guided for longitudinal sliding movement within said hollow interior portion; a hand grip member positioned outside of said bottom rail for raising and lowering said closure member, said hand grip member including a flat base portion, the upper corners 35 of which are rounded, overlying said flat surface portion of said bottom rail for sliding movement laterally of said closure member and a longitudinally extending finger engaging flange projecting perpendicularly from the upper edge of said flat base portion, the ends of said flange being in the form of tabs bent to conform with the rounded upper corners of said flat base portion; spring means normally urging said latch bolt to extended position; and means rigidly interconnecting said latch bolt and said grip member whereby lateral movement of said grip member will cause a corresponding longitudinal movement of said latch bolt.

3. A combined latch operator and lift device for a vertically sliding closure member having a bottom rail of extruded aluminum provided with spaced slots in the inner 55 side wall thereof and including a hollow interior portion and an exterior portion presenting a flat vertical surface, comprising: a latch bolt having spaced threaded apertures therein guided for longitudinal sliding movement within said hollow interior portion; a hand grip member for raising and lowering said closure member having a finger engaging portion and a flat base portion for sliding movement laterally of said closure over said flat vertical surface of said bottom rail; and means rigidly interconnecting said latch bolt and said grip member whereby lateral movement of said grip member will cause a corresponding longitudinal movement of said latch bolt, said interconnecting means including a pair of screws having a threaded portion for reception in said threaded apertures in said latch bolt, an enlarged portion providing a shoulder as a spacer adjacent said threaded portion to limit the distance said screws may be threaded into said latch bolt and a further enlarged head portion, the distance between said shoulder and said head portion being such as to provide just sufficient clearance between said flat base portion of said hand grip member and said flat vertical surface of

said bottom rail for easy sliding movement when said screws are passed through apertures in said flat base portion of said hand grip member and said slots in the inner side wall of said bottom rail.

4. A construction for an extruded metal window sash adapted to slide vertically in a trackway having vertically spaced apertures therein, said window sash including a combined latch operator and lift device, comprising: a bottom rail including vertical side walls joined by spaced horizontal web members to provide a hollow interior portion, the inner side wall being provided with spaced slots and an external flat surface portion; a latch bolt for insertion in a selected one of said spaced apertures in said trackway guided for longitudinal sliding movement in said hollow interior portion of said bottom rail, said latch bolt having spaced threaded apertures therein; a hand grip member positioned outside of said bottom rail for raising and lowering said closure member, said hand grip member having a finger engaging portion and a flat base portion for sliding movement laterally of said window over said external flat surface of said inner side wall, said flat base portion having a pair of spaced apertures therein and said finger engaging portion being an integral flange extending perpendicularly from along the upper edge of said flat base portion; and a pair of screws passing through said apertures in said base portion of said hand grip member and said slots in said inner wall of said bottom rail member and threaded into said threaded apertures in said latch bolt to rigidly interconnect said hand grip member and said latch bolt, whereby lateral movement of said hand grip member will cause a corresponding longitudinal sliding movement of said latch bolt relative to said bottom rail.

5. A construction for an extruded metal window sash adapted to slide vertically in a trackway having vertically spaced apertures therein, said window sash including a combined latch operator and lift device, comprising: a bottom rail including spaced vertical side walls joined by spaced horizontal web members to provide a hollow interior portion, the inner side wall being provided with spaced slots and an external flat surface portion and one of said web members having an ear struck therefrom into said hollow interior portion; a latch bolt having an outer end for insertion in a selected one of said spaced apertures in said trackway and an inner end guided for longitudinal sliding movement in said hollow interior portion of said bottom rail, said latch bolt having spaced threaded apertures therein; a coil spring positioned in said hollow interior portion of said bottom rail between the inner end of said latch bolt and said ear struck from said web member whereby said latch member is constantly urged toward extended position; a hand grip member positioned outside of said bottom rail for raising and lowering said closure member, said hand grip member having a finger engaging portion and a flat base portion for sliding movement laterally of said window over said external flat surface portion of said inner side wall, said flat base portion having a pair of spaced apertures therein and said finger engaging portion being an integral flange extending perpendicularly from along the upper edge of said flat base portion; and a pair of screws passing through said apertures in said base portion of said hand grip member and said slots in said inner wall of said bottom rail member and threaded into said threaded apertures in said latch bolt, to rigidly interconnect said hand grip member and said latch bolt, whereby lateral movement of said hand grip member will cause a corresponding longitudinal sliding movement of said latch bolt relative to said bottom rail.

6. A metal window construction for a vertically sliding closure member having a laterally projecting latch bolt, comprising: a window frame including a pair of side frame members, at least one of said side frame members having an inwardly facing, longitudinally extending channel therein and a longitudinal, inwardly extending flange

disposed parallel to said channel; and guide tracks secured to said side frame members with one of said guide tracks abutting said flange, said guide tracks including a U-shaped portion receiving said closure member for vertical sliding movement and being located over said longitudinal channel with the base of said U-shaped portion being flat throughout its width and being provided with a series of spaced apertures for the reception of said latch bolt and projection thereof into said channel.

10 7. A metal window construction for a vertically sliding closure member having a laterally projecting latch bolt, comprising: a window frame including a pair of side frame members, at least one of said side frame members having an inwardly facing longitudinally extending channel therein and a longitudinal, inwardly extending flange parallel with said channel; guide tracks secured to said side frame members with one of said guide tracks abutting said flange, said guide tracks including a U-shaped portion receiving said closure member for vertical sliding movement and having a flat base located over said longitudinal channel; and tabs struck downwardly and inwardly from the base of said U-shaped portion of said guide track into said longitudinal channel to form a series of openings for the reception of said latch bolt.

25 8. A metal window construction, comprising: a window frame including side frame members at least one of which has an inwardly facing longitudinally extending channel therein and a longitudinal, inwardly extending flange parallel to said channel; guide tracks secured to said side frame members, with one of said guide tracks abutting said flange, said guide tracks including a U-shaped portion, the base of which overlies said longitudinally extending channel and is flat throughout its width, a series of spaced apertures being provided therein; and a closure member 30 received by said U-shaped portion of said guide tracks for vertical sliding movement, said closure member having at least one laterally projecting latch member for reception into said longitudinally extending channel through a selected one of said series of apertures in said base of said U-shaped portion of said guide tracks.

35 9. A metal window construction, comprising: a window frame including a pair of side frame members, at least one of which has an inwardly facing, longitudinally extending channel therein and a longitudinal, inwardly extending flange disposed parallel to said channel; guide tracks secured to said side frame members with one of said guide tracks abutting said flange, said guide tracks including a U-shaped portion, the base of which overlies said channel and is flat throughout its width, a spaced series of 40 tabs being struck downwardly and outwardly therefrom into said channel to form a series of apertures having cam surfaces associated therewith; and a closure member received by said U-shaped portion of said guide track, for vertical sliding movement, said closure member having at least one laterally projecting latch bolt having a bevelled end providing a cam surface lying in substantially the same vertical plane as the cam surfaces provided by said tabs, said latch bolt being constantly urged by spring means toward reception in said longitudinal channel 45 through a selected one of said apertures, the arrangement being such that upon raising the closure member said latch bolt will be automatically cammed from each successive aperture, but in order to lower the closure member, the latch bolt must be manually retracted from the selected one of said apertures in which it is positioned.

50 10. A metal window construction for a vertically sliding closure member having a laterally projecting latch bolt, comprising: a window frame including a pair of side frame members, at least one of said side frame members having an inwardly facing, longitudinally extending channel therein and a longitudinal, inwardly extending flange disposed parallel to said channel; guide tracks secured to said side frame members with one of said guide tracks 55 abutting said flange, said guide tracks including a U-

shaped portion receiving said closure member for vertical sliding movement located over said longitudinal channel with the base of said U-shaped portion being flat throughout its width, provided with a series of spaced apertures for the reception of said latch bolt and projection thereof into said channel; a hand grip for raising and lowering said closure member; means mounting said hand grip on said closure member for sliding movement laterally thereon; and means rigidly interconnecting said hand grip and latch bolt to retract said latch bolt upon lateral movement of said hand grip in a direction inwardly of said window frame.
